(57) **CLAIM**

The ornamental design for a ceiling fan blade, as shown and described.

DESCRIPTION

FIG. 1 is a bottom perspective view of a ceiling fan blade in the environment of a ceiling fan.

FIG. 2 is a top perspective view of the ceiling fan blade of FIG. 1;

FIG. 3 is a bottom perspective view of the ceiling fan blade of FIG. 1;

FIG. 4 is a left side view of the ceiling fan blade of FIG. 1;

FIG. 5 is a right side view of the ceiling fan blade of FIG. 1;

FIG. 6 is a front view of the ceiling fan blade of FIG. 1;

FIG. 7 is a rear view of the ceiling fan blade of FIG. 1;

FIG. 8 is a top view of the ceiling fan blade of FIG. 1; and,

FIG. 9 is a bottom view of the ceiling fan blade of FIG. 1. The broken lines in FIG. 1 showing a ceiling fan illustrate environmental subject matter. The broken lines in FIGS. 2 through 9 drawings illustrate portions of the ceiling fan blade. All broken lines form no part of the claimed design.

1 Claim, 8 Drawing Sheets
